STEAM-JACKETED ASPHALT BUCKET

John I. Hurst, Indianapolis, Ind., assignor to
 Hetherington & Berner Inc., Indianapolis, Ind.,
 a corporation of Indiana

Application October 19, 1933, Serial No. 694,278

3 Claims. (Cl. 221—118).

In the manufacture of such materials as paving compositions which involve the mixing of aggregate and melted bitumen accurate proportioning of the ingredients requires a weighing of the quantity of bitumen supplied to each batch of material. In the past, the melted bitumen has been weighed in dumping buckets which may or may not have been steam-jacketed. If the buckets were not steam-jacketed, a part of the melted bitumen introduced into the bucket would congeal on the walls thereof, thus gradually building up an objectionable bitumen coating and also making it necessary to weigh the empty bucket after each operation. When steam-jacketed buckets were used the steam was supplied to and conducted from the jacket through flexible hoses, and changes in the disposition of these hoses which occurred upon each inversion of the bucket would affect the indicated weight of the bucket and render accurate proportioning of the ingredients impossible.

It is the object of my invention to produce a steam-jacketed weigh-bucket which will not have the disadvantages present in buckets previously used for the weighing of melted bitumen. More specifically, it is my object to produce a weigh-bucket in which the melted bitumen will not congeal to build up a film of gradually increasing thickness. A further object of my invention is to produce a weigh bucket which may be emptied without inversion and thus to avoid such displacement of the flexible steam hoses as would affect the indication of weight.

In carrying out my invention, I suspend the weigh bucket from a scale or otherwise associate it with the scale so that the weight of the bucket and its contents may be quickly determined. Associated with the bucket I provide means for guiding it in a vertical plane while holding it in an upright position. I provide for the discharge of the bucket contents at the bottom of the bucket and control this discharge through the means of a suitable valve. The bucket and valve are steam-jacketed so that the bitumen will be maintained in liquid condition while in the bucket and while being discharged therefrom.

The accompanying drawings illustrate my invention: Figs. 1 and 2 are end and front elevations respectively of my improved bucket; and Figs. 3 and 4 are sectional views on an enlarged scale illustrating details of construction, Fig. 3 being a horizontal section through the axis of the discharge valve on the line 3—3 of Fig. 4, and Fig. 4 being a vertical transverse section on the line 4—4 of Fig. 3.

My bucket comprises end walls 10 and side walls 11 the lower portions of which slope inwardly toward each other, the extreme lower edges of the side walls being spaced apart as indicated at 12 in Fig. 4 to form a discharge opening which extends for substantially the entire length of the bucket. Secured to the lower edges of the walls 11 is a hollow cylindrical valve casing 13. Conveniently, this valve casing 13 is formed of a length of pipe having a diameter somewhat greater than the width of the slot 12, such pipe being provided with a slot substantially equal in width to that of the slot 12 and being secured to the lower edges of the side walls 11 as by welding. At its ends, the valve casing 13 is welded to the end walls 10 of the bucket, such end walls being provided with openings substantially equal in diameter to the casing 13.

The bucket proper and the valve casing 13 are steam-jacketed. The jacket shown in the drawings comprising plates 15 which are mounted outside of and in spaced relation to the side walls 11 of the bucket, the edges of such plates being bent inwardly and secured to the outer surface of the side walls to prevent escape of steam. If necessary stays comprising spacing blocks 16 and rivets 17 may be provided wherever necessary to prevent separation of the walls 11 and plates 15 under the influence of the pressure of the steam between them.

The lower portion of the steam jacket may be formed of a length of pipe 18 of larger diameter than the valve casing 13. The pipe 18 is provided with a longitudinal slot the edges of which are secured to the lower edges of the plates 15, as is clear from Fig. 4. The pipe 18 extends between the end walls 10 and is secured to such end walls, as by welding.

At their lowermost points, the casing 13 and pipe 18 are provided with axially extending series of aligned openings which receive short discharge pipes 20, preferably welded to the casing and to the jacket as shown in Fig. 4. The inner ends of the pipes 20 are finished flush with the inner surface of the casing 13 in order that they may be closed by a valve member 21 which lies within the casing 13.

The valve member 21 is arcuate in cross-section, its outer surface conforming to the curvature of the inner surface of the casing 13. At its ends, the valve member 21 has secured to it, as by welding, inwardly extending arms 22 which, on the axis of the casing 13, are provided with holes for the reception of the inner ends of valve-shafts 23. Preferably, in order to insure

a rigid connection between the shafts 23 and the arms 22, the holes of the arms and the inner ends of the shaft are made square and each shaft is welded to its associated arm.

5 Each of the shafts 22 extends outwardly through a stuffing box 25 which is mounted on a cover plate 26 adapted to be secured, as by means of bolts 27, to the adjacent end wall 10 of the bucket. A spacing collar or washer 28 10 surrounding the shaft 23 may be secured to the inner face of each cover plate 26.

For the purpose of operating the valve, the shafts 23 are connected to an operating bar 30 which extends longitudinally of the bucket and 15 is provided with in-turned ends 31 to which the outer ends of the shafts 23 are respectively connected.

Near opposite corners of the bucket, the steam jacket is provided with fittings adapted for connection to a steam supply conduit 35 and a steam discharge conduit 36. These conduits are flexible in order not to interfere with that free 20 vertical movement of the bucket which is necessary in the securing of accurate weighing.

25 The bucket may be mounted upon the mixing machine in conjunction with which it is to be used. A portion of such machine, comprising one wall of an aggregate hopper, is indicated at 38 in Figs. 1 and 2. Upon a bracket 38' carried 30 by the hopper-wall 38 there is mounted a scale 39 from which is suspended a yoke 40 having down-turned ends 41 which receive the weigh-bucket between them. Near the upper edge of each end of the bucket there is secured a block 35 42 rigid with which is an outwardly extending trunnion adapted to be received in an eye on the adjacent yoke-end 41. The connection of the yoke 40 to the scale is universal in character 40 in order to permit the freedom of movement necessary to accurate weighing.

At each end of the weigh bucket I provide a pair of vertical guide members 45, conveniently in the form of angle irons. The two guides of each pair are spaced sufficiently far apart 45 to receive slidably between them the trunnion block 42 at the top of the bucket and the stuffing box 25 near the bottom of the bucket. By this means a guide is provided which holds the bucket in upright position while permitting its free vertical movement.

The bucket may discharge upon an inclined plate or trough 50 by which the contents of the bucket are conveyed to the mixer 51. The trough or plate 50 may, like the walls of the bucket, be 55 steam-heated to prevent the melted bitumen from adhering to it.

When the bucket is being used, steam is supplied to the jacket through the pipe 35 and discharged through the pipe 36, thus maintaining 60 the bucket at an elevated temperature. Normally, the valve-operating bar 30 is in the position illustrated in Figs. 1 and 2 with the valve

member 21 covering the upper ends of the short pipes 20. With the valve in this position, bitumen is placed in the bucket until the bucket contains the desired weight as indicated upon the scale 39.

When the bitumen has thus been weighed, the 5 valve operating bar is lifted, thus swinging the valve member 21 to the position illustrated in Figs. 3 and 4 where it uncovers the upper ends of the pipes 20 and permits melted bitumen to be discharged. Because of the steam-jacketing 10 of the bucket itself, of the valve-casing 13, and of the discharge pipes 20, substantially all the bitumen is discharged.

I claim as my invention:

1. In a device of the class described, a hopper, 15 a longitudinally extending length of pipe disposed at the bottom of said hopper, said pipe being provided at its top with a longitudinal slot, said hopper having sloping walls joined to said pipe along opposite sides of said slot, a plurality of discharge nozzles extending downwardly from said pipe, an arcuate valve member mounted within said pipe and swingable about the pipe-axis to open and close the upper ends of said nozzles, and a steam jacket for said hopper, said 20 jacket including a portion surrounding said pipe and said nozzles extending through such pipe-surrounding portion of said jacket.

2. In a device of the class described, a hopper, 25 a longitudinally extending length of pipe disposed at the bottom of said hopper, said pipe being provided at its top with a longitudinal slot, said hopper having sloping walls joined to said pipe along opposite sides of said slot, a plurality of discharge nozzles extending downwardly from 30 said pipe, valve means disposed within said pipe for controlling the discharge of the hopper-contents through said nozzles, and a steam jacket for said hopper, said jacket including a portion surrounding said pipe and said nozzles extending through such pipe-surrounding portion of 35 said jacket.

3. In a device of the class described, a hopper, 40 a longitudinally extending length of pipe disposed at the bottom of said hopper, said pipe being provided at its top with a longitudinal slot, said hopper having sloping walls joined to said pipe along opposite sides of said slot, a steam jacket for said hopper including plates disposed beneath and generally parallel to said 45 sloping walls, a second pipe surrounding and of materially larger diameter than said first pipe, said second pipe being provided at its top with a longitudinal slot to the side edges of which the lower edges of said plates are secured, discharge nozzles extending vertically through the walls of said pipes at the bottom thereof, and means disposed within said first named pipe for 50 controlling the discharge of the hopper contents through said nozzles.

JOHN I. HURST.
